UNITED STATES PATENT OFFICE.

JOHN LANGLY JAMES, OF CHARLOTTE, NORTH CAROLINA.

BABY BED.

Application filed June 15, 1922. Serial No. 568,588.

To all whom it may concern:

Be it known that I, JOHN L. JAMES, a citizen of the United States, residing at Charlotte, in the county of Mecklenburg 5 and State of North Carolina, have invented a new and useful Baby Bed, of which the following is a specification.

This invention aims to provide a crib which may be folded up readily into small 10 compass, when not in use, novel means being provided for raising and lowering the bottom of the crib, and the crib being wheel-mounted to the end that it may be rolled about readily, from place to place.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, within 25 in the scope of what is claimed, changes in the precise embodiment of the invention shown can be made without departing from the spirit of the invention.

In the accompanying drawings:—

30 Figure 1 shows in side elevation, a device constructed in accordance with the invention; Figure 2 is a cross section on the line 2—2 of Figure 1; Figure 3 is a top plan wherein the crib is shown in folded condition; Figure 4 is a section on the line 4—4 of Figure 1; Figure 5 is a section on the line 5—5 of Figure 1; Figure 6 is a fragmental end view showing the crib folded; Figure 7 is a perspective view illustrating 35 the mounting of the end member; and Figure 8 is a fragmental end elevation showing the crib in the position depicted in Figure 2.

The crib forming the subject matter of 45 this application includes a fixed side 1 carrying inwardly projecting posts 2 which may be considered as parts of the side 1, the side including a bottom rail 3. The numeral 4 marks a fixed side which is approximately 50 one half the height of the fixed side 1, the side 4 being provided with inwardly projecting posts 5 and including a bottom rail 6, the sides 4 and 1 being disposed in parallel relation. Ends 7 are supplied, and are 55 connected by hinges 8 with the posts 5 of the side 4. Hinges 9 are secured to the ends

7 and include tubular elements 10 mounted for reciprocation on guide rods 11 on the posts 2 of the side 1 and disposed parallel to the side 1. The device includes a foldable side section 12 connected by hinges 14 to the fixed side 4.

Latches 15 are pivoted at 16 to the ends of the side 1. Latches 17 are pivoted at 18 to the ends of the downwardly foldable side 60 section 12. The ends 7 are supplied, adjacent to their free edges, with keepers 19 adapted to cooperate with the latches 15. The posts 5 are supplied with keepers 20, 65 adapted to cooperate with the latches 17. 70 Incidentally, it may be noted that the side 1, the side 4, the ends 7 and the downwardly foldable section 12 may include panels of wire netting, indicated by the numeral 21.

The crib includes a vertically movable bottom 22. Flexible elements 23 are connected to the bottom 22 adjacent to the fixed side 1, and are seated detachably on guide sheaves 24 mounted to rotate on the posts 80 2 of the side 1. Flexible elements 25 are secured to the bottom 22 adjacent to the fixed side 4. The flexible elements 25 and the flexible elements 23 are rove over guide sheaves 26 carried by the posts 5 of the fixed side 4 and permanently assembled with the said guide sheaves 26. The flexible elements 25 and 23 are secured as indicated at 27, to the downwardly foldable side section 12 in spaced relation to the hinges 14 whereby 90 the said side section 12 is connected to the fixed side 4.

Forks 28 are provided, and include side bars 29 connected by a bridge 30. The ends of the side bars 29 project upwardly beyond the bridge 30 as shown at 31 in Figure 4. The bottom rail 6 and the bottom rail 3 at one end of the crib, are received between the ends 31 of the side bars 29. Securing elements 32 pass forwardly through the bottom rail 6 and through the bottom rail 3 and engage the bridges 30, the forks 28 being held against rotation, owing to the engagement between the ends 31 of the side bars 29 and the rails 6 and 3. Wheels 33 100 are journaled for rotation on the forks 28. Forks 34 are provided, each fork comprising side arms 35 connected by an end piece 36 whereon is superposed a washer 37. The side arms 35 of each fork 34 are connected 105 by a bridge 38. A tubular spacer 39 is interposed between the bridge 38 and the end 110

piece 36. The washers 37 abut against the rails 3 and 6, through the rails 3 and 6, through the washer 37, through the end piece 36, the spacer 39 and the base 38 pass securing elements 40. The forks 34 can turn on the securing elements 40. Wheels 41 are journaled on the forks 34. The construction is such that the wheels 33 have no movement about a vertical axis, whereas the 10 wheels 41 have movement about a vertical axis, it being possible, therefore, to trundle the crib readily about and to steer the same in any desired direction.

When the crib is set up for use, as shown 15 in Figures 1 and 2, the ends 7 are alined with the posts 2 and 5, the latches 17 are connected with the keepers 20, to keep the side section 12 from folding downwardly and outwardly, and the latches 15 are assembled with the keepers 19, to hold the 20 ends 7 against swinging movement on the hinges 8. The bottom 22 is in the lowered position delineated in Figure 2.

The latches 17 may be disengaged from 25 the keepers 20 and, thereupon, the section 12 may be swung downwardly into the dotted line position shown in Figure 2. When the section 12 is swung downwardly as aforesaid, the section acts as a lever, and draws 30 upon the flexible elements 23 and 25, the flexible elements riding over the sheaves 24 and 26, and raising the bottom 22 until the bottom is in horizontal alinement, approximately, with the upper edge of the fixed side 4 as depicted in dotted line in Figure 3. When the section 12 is swung downwardly the latches 17 which are pivoted to the said section, may be engaged with keepers 42 located on the posts 5 adjacent to the 40 lower ends of the posts. Thus, the downwardly foldable section 12 and the bottom 22 will be held in the position shown in dotted lines in Figure 2. When the bottom 22 is raised, it is obvious that an infant may be removed readily from the bottom, it being unnecessary to reach downwardly into the crib, the work incident to handling the infant being decreased accordingly, and all 45

of the bedding being rendered readily accessible.

When the occasion for the use of the crib has passed, the latches 15 are cast off from the keepers 19 and the ends 7 are swung inwardly, on their hinges 8, until the ends lie parallel to the side 1, as shown in Figure 3, 55 the tubular elements 10 of the hinges 9 riding inwardly, toward each other, on the guide rods 11. The flexible elements 25 and 23 are detached from the sheaves 24 and the bottom 22 is stood up edgewise, as shown in 60 Figure 3. The fixed side 1, on the one hand, and the side forming members 4 and 12 on the other hand, are moved toward each other, until the posts 5 and 2 abut, as shown in Figure 6, whereupon the latches 15 on 65 the side 1 are engaged with the keepers 20 on the posts 5, as disclosed in Figure 6, the crib then being held in the compact and collapsed position disclosed in Figure 3.

What is claimed is:—

1. A crib comprising fixed sides; a downwardly foldable section hinged to one side; ends hinged to one side; means for holding the ends releasably against movement; means for mounting the ends slidably upon 75 the other side; a movable bottom; and means for connecting the bottom to the section, to secure a raising of the bottom when the section is folded downwardly.

2. A crib comprising fixed sides; a downwardly foldable section hinged to one side; ends hinged to one side; means for holding the ends releasably against movement; a guide carried by one side; means for mounting the ends hingedly and slidably on the 85 guide; a movable bottom; and means for connecting the bottom to the section to secure a raising of the bottom when the section is folded downwardly.

In testimony that I claim the foregoing 90 as my own, I have hereto affixed my signature in the presence of two witnesses.

JOHN LANGLY JAMES.
